RAILWAY TRAFFIC CONTROLLING
APPARATUS

Earl M. Allen, Swissvale, Pa., assignor to The
Union Switch & Signal Company, Swissvale,
Pa., a corporation of Pennsylvania

Application April 23, 1931, Serial No. 532,174
Renewed September 15, 1932

19 Claims. (Cl. 246—3)

My invention relates to railway traffic controlling apparatus, and particularly to apparatus of the type comprising traffic governing devices for both directions of traffic selectively controlled 5 by manually operable means to permit traffic movements in one direction or the other.

One feature of my invention is the provision of means for permitting traffic movements in a given direction only if an approach locking relay 10 for that direction is deenergized while an approach locking relay for the opposite direction is energized.

I will describe one form of apparatus embodying my invention, and will then point out the 15 novel features thereof in claims.

The accompanying drawings, Figs. 1a and 1b, when placed end to end, with Fig. 1a on the left, constitute a diagrammatic view showing one form of apparatus embodying my invention.

Referring to the drawings, a stretch of railway track A—I is shown equipped with signals 20 designated S^{2a}, S^{2b}, S^{2c}, S⁴, S⁵, S⁶, S^{8a}, S^{9b} and S^{9c}, respectively, for governing traffic normally moving westward, that is, from right to left as 25 shown in the drawings. Eastbound traffic movements may also at times be permitted over stretch A—I by signals designated by the reference characters S^{1a}, S^{1b}, S^{1c}, S^{3a}, S^{3b}, S⁷, S^{8a}, S^{8b} and S^{8c}, respectively. Signals S^{1a}, S^{1b} and 30 S^{1c} operate contacts 5, 6 and 7, respectively, each of which is closed when and only when its signal is indicating "stop". Signals S^{9a}, S^{9b} and S^{9c} operate corresponding contacts 5, 6, and 7, respectively, each of which is closed when and 35 only when its signal is indicating "stop".

Rails 1 and 1^a of stretch A—I are divided by insulated joints 2 to form a plurality of sections designated A—B, B—C, C—D, D—E, E—F, F—G, G—H and H—I, respectively. Each of 40 these sections is provided with a track circuit including a battery 3 connected across the rails adjacent one end of the section and a relay designated by the reference character T with a distinguishing exponent and connected across the 45 rails adjacent the opposite end of the section.

Track switches designated by the reference characters J¹, J² and J³ are located in sections B—C, D—E and G—H, respectively. As here shown, switch J¹ is arranged to be operated between normal and reverse positions by a motor 50 designated by the reference character M. Switch J² may be operated by any suitable manually operated mechanism, not shown in the drawings. A lock bar b is rigidly secured to the 55 switch J² for engagement by a dog a, by means

of which the switch may be locked in its normal position in which it is shown in the drawings. Dog a is actuated by a manually operable lever X which has normal and reverse positions designated by the reference characters m and r, 5 respectively. Movement of lever X is controlled electrically by means of a lock magnet d having an armature provided with a dog 60 for engagement with a notch 61 of a locking segment g. Segment g is rigidly connected to lever X. 10 Switch J³ may be operated by any suitable means, not shown in the drawings.

Eastbound traffic movements into portion B—H of stretch A—I are controlled by signals 15 S¹. Westbound traffic movements into portion B—H of stretch A—I are controlled by signals S⁹.

A lever designated by the reference character V¹, and having a normal position n, a reverse position to the left k, and a reverse position to the right r, is provided for controlling signals S¹. Lever V¹ operates a contact 4^{nk} which is closed while lever V¹ occupies its n position or any position to the left of its n position, but which is open when lever V¹ is moved toward the right from its n position. Lever V¹ also operates a contact 21 which is closed when and only when lever V¹ occupies its r position. 20

An approach locking relay associated with signals S¹, and designated by the reference character P^B, is controlled in part by contact 4^{nk} of lever V¹ and in part by contacts 5, 6, and 7 of signals S¹. The control of relay P^B by these contacts is such that this relay will become deenergized whenever any one of these contacts is 25 opened.

A slow pick-up relay designated by the reference character L^B is also controlled by the same lever contact 4^{nk}, by contacts 5, 6, and 7 of signals S¹, and by a back contact of relay P^B. 30

A stick relay K^B has a pick-up circuit controlled by front contacts 12 and 13 of relays P^B and T², respectively, and has a stick circuit controlled by a front contact of relay P^B. 35

A lever V³, similar to lever V¹, is provided for controlling signals S⁹. Lever V³, however, operates a contact 4^{nr} which is closed while lever V³ occupies its n position or any position to the right of its n position, but which is opened when lever V³ is moved towards the left from its n position. Lever V³ also operates a contact 42 which is closed when and only when lever V³ occupies its k position. 40

An approach locking relay P^H is controlled similarly to approach locking relay P^B, already 45

described, so that when any one of the contacts, 4^{nr} of levers V³ and 5, 6 and 7 of signals S⁹, is open, relay P^H will be deenergized. A slow pick-up relay L^H is controlled similarly to relay L^B, 5 as already described, and a stick relay K^H is controlled similarly to stick relay K^B.

Relays K^B and K^H control a circuit which includes three polarized relays connected in series 10 each of which is designated by the reference character Q with a distinguishing exponent. Relays Q are so designed that their polar contacts, after becoming closed when the corresponding relay is energized in a given direction, will remain closed in the corresponding position 15 until the relay is energized in the opposite direction. When relay K^B is energized and relay K^H is deenergized, relays Q are energized by current of normal polarity for controlling westbound traffic movements. When relay K^H is energized 20 and relay K^B is deenergized, relays Q will be energized by current of reverse polarity for controlling eastbound traffic movements.

When lever V³ is moved from its *n* to its *k* position, causing relays P^H and K^H to become deenergized and causing its contact 42 to close, relay Q³ will become energized in the normal direction, causing its contact 45 to remain closed in the position shown in the drawings. If switch J³ is in its normal position, if relay Q³ remains energized, and if track section G—H is unoccupied, signal S^{9a} will be operated to its proceed position. If, however, relay Q³ becomes deenergized, or if relay T⁷ is deenergized, signal S^{9c} will be operated to its proceed position.

Polarized relay Q² controls, in part, a lock relay W which, in turn, controls lock magnet *d* for switch J². Relay W is also controlled by a reverse polar contact of a polarized relay Y which is controlled by a back contact of an indication relay N and by pole-changing contacts operated by a lever V². Lever V² has a normal position *m* and a reverse position *r*. Relay W is also controlled by an approach relay *t*, by a manually operable push button *h*, and by a contact *f*. Contact *f* is operated by the door of a case in which magnet *d* and lever X are enclosed. Contact *f* is normally open when this door is closed but becomes closed when the door is opened.

A switch indication relay U is controlled by a contact 62, which is operated by lever X, and by a contact 63 which is operated by switch J². Contact 62 is closed when and only when lever X is in its normal position, and contact 63 is closed when and only when switch J² is in its normal position.

Indication devices, here shown as electric lamps e^R and e^N, are controlled by front and back points of contact 64 of relay N, respectively.

When lever V¹ is moved to the right of its *n* position, causing relay K^B to be deenergized, and while relay K^H is energized, relay Q¹ will be energized in the reverse direction, and hence relay R^a will be energized, causing signal S^{3a} to be operated to the proceed position. If, after relay Q¹ becomes energized in the reverse direction, the circuit for this relay should be broken, causing its neutral contact to open at its front point 70 and to close at its back point, relay R^b will become energized for causing signal S^{3b} to indicate "proceed". When either relay R^a or R^b is energized and when lever V¹ is at the same time in its *r* position while track relay T² is energized 75 and switch J¹ is in its normal position, the arm of

signal S^{1a} will be moved to the proceed position.

Motor M is provided with a circuit by which it is caused to move switch J¹ to its normal or its reverse position according as the polarity of the current supplied to this circuit is normal or reverse. Only a portion of this circuit, including 5 wires 15 and 16 and contact 17 of relay K^B, is shown. It will be noted, therefore, that motor M can be operated for moving switch J¹ only when relay K^B is energized.

Levers V¹, V² and V³ may be grouped together in some central location such, for example, as a train dispatcher's office.

In each of the drawings, the contacts operated by the various relays are identified by numbers, 15 such numbers having exponents when the contacts are not shown adjacent the respective relays by which they are operated. The exponent for each of these contact numbers comprises the reference character and exponent for the respective relay. For example, the exponent T⁷ for contact 47^{T7}, shown in the circuits for signals S^{9a} and S^{9c}, comprises the reference character T and its exponent 7 for track relay T⁷ which 20 operates contact 47^{T7}.

Having described, in general, the arrangement and control of the apparatus embodying my invention, I will now trace in detail the operation of the various parts.

As shown in the drawings, all parts are in the 30 normal condition, that is, levers V¹, V² and V³ are in their normal positions, signals S¹, S², S³, S⁸ and S⁹ are indicating "stop", and stretch A—I is unoccupied. With lever V¹ in its *n* position, approach locking relay P^B is energized by 35 a stick circuit passing from terminal *x* of a source of current not shown in the drawings, through contact 4^{nr} of lever V¹, contacts 5, 6 and 7 of signals S^{1a}, S^{1b} and S^{1c}, respectively, contact 8 of relay P^B, and the winding of relay P^B to terminal *o* of the same source of current. With relay P^B energized and with track relay T² energized, the pick-up circuit for relay K^B is closed, passing from terminal *x*, through contact 12 of relay P^B, contact 13 of relay T², and the winding of relay K^B to terminal *o*. The stick circuit for relay K^B is also closed, passing from 45 terminal *x*, through contact 12 of relay P^B, contact 14 of relay K^B and the winding of relay K^B to terminal *o*. With relay K^B energized, the portion of the circuit shown for motor M is closed 50 through contact 17 of relay K^B.

With lever V³ in its *n* position, relay P^H is energized by a stick circuit similar to that previously traced for relay P^B except passing through a contact 4^{nr} of lever V³ instead of through a contact 4^{nk}. A pick-up circuit and a stick circuit for relay K^H, similar to the pick-up and stick circuits traced for relay K^B, are also closed.

With lever X in its normal position, and with switch J² in its normal position, switch indication relay U is energized by a circuit passing from terminal *x*, through contact 62 of lever X, contact 63 of switch J², and the winding of relay U 65 to terminal *o*. Since track relays T⁵ and T⁶ are energized, approach relay *t* is energized by a circuit passing from terminal *x*, through contact 48 of relay T⁶, contact 49 of relay T⁵, and the winding of relay *t* to terminal *o*.

Indication relay N is deenergized, and hence indicator lamp e^N is lighted by a circuit passing from terminal *x*, through back point of contact 64 of relay N, and lamp e^N to terminal *o*.

I will assume that with all parts thus in their 75

normal condition, the operator at the dispatcher's office desires to clear signal S^{9a} for a westbound train. He will therefore move lever V^3 to its k position. This movement of lever V^3 opens contact 4^{nr} , causing relay P^H to become deenergized. The deenergization of relay P^H causes its contact 12 to open, and hence relay K^H also becomes deenergized. With relay K^H deenergized, a circuit is completed for energizing relays Q in the 10 normal direction, passing from terminal x , through back contact 23 of relay R^a , back contact 24 of relay R^a , front point of contact 25^{KB} , winding of relay Q^1 , contact 26 of relay T^3 , winding of relay Q^2 , front point of contact 27^a of relay 15 T^4 , contact 28 of relay U , contact 29 of relay T^5 , contact 30 of relay T^6 , winding of relay Q^3 , back points of contacts 31 and 32 of relay K^H , wires 33 and 35 , and the front point of contact 36^{KB} to terminal o . Relay Q^3 thereupon closes its 20 contact 46 at its front point and retains its polar contact 45 closed in the normal position shown in the drawings. With relay Q^3 thus energized and with relay K^H deenergized, and with contact 42 of lever V^3 closed because lever V^3 has been 25 moved to its k position, a circuit is completed for causing signal S^{9a} to indicate proceed, passing from terminal x , through contact 42 of lever V^3 , contact 43 of switch J^3 , back contact 44^{KH} , polar contact 45 , front point of contact 46 of relay Q^3 , front point of contact 47^{T^1} , and the mechanism 30 of signal S^{9a} to terminal o .

If, before a train passes signal S^{9a} , the operator decides to return signal S^{9a} to its stop position in order to arrange for some other traffic movement, he will return lever V^3 to its n position. Contact 42 of lever V^3 being thereby opened, the arm of signal S^{9a} will return to its stop position. With lever V^3 in its n position, a circuit will now be completed for relay L^H , passing from terminal 40 x , through contact 4^{nr} of lever V^3 , contacts 5 , 6 , and 7 of signals S^{9a} , S^{9b} and S^{9c} , respectively, back point of contact 8 of relay P^H , and the winding of relay L^H to terminal o . Upon the lapse of a given period of time, relay L^H will close its front 45 contact 11 , thereby completing a pick-up circuit for relay P^H passing from terminal x , through contact 4^{nr} of lever V^3 , contacts 5 , 6 and 7 of signals S^9 , contact 11 of relay L^H , and the winding of relay P^H to terminal o . Relay P^H , upon becoming thus energized, completes its stick circuit previously traced through the front point of its contact 8 , and opens, at the back point of its contact 8 , the circuit for relay L^H , causing relay L^H to become deenergized. With relay P^H energized, the pick-up circuit for relay K^H is closed, causing relay K^H to again become energized. With relay K^H energized, the operator can now 50 arrange for the traffic movement desired.

I will now assume that all parts of the apparatus have again been returned to the normal condition, and that the operator has again cleared signal S^{9a} for a westbound train. When such a train passes signal S^{9a} , it will deenergize relay T^7 and so cause the arm of signal S^{9a} to return 60 to the stop position. If, now, the operator returns lever V^3 to its n position, the circuit previously traced for relay L^H will be again completed. When the train passes out of section $H-I$, a second pick-up circuit will be completed 65 for relay P^H , passing from terminal x , through contact 4^{nr} of lever V^3 , contacts 5 , 6 and 7 of signals S^9 , back contact 9 of relay T^7 , contact 10 of relay T^8 , and the winding of relay P^H to terminal o . Relay K^H can not, however, become 70 energized until the train has passed out of section 75

tion $G-H$ thereby permitting relay T^7 to close its contact 13 for completing the pick-up circuit for relay K^H .

As the train proceeds westward, relays T^6 , T^5 , T^4 and T^3 , by becoming successively deenergized, 5 keep the circuit for relays Q open. It will thus be seen that from the time a train passes signal S^9 until it leaves section $C-D$, the circuit for relays Q is constantly open, making it impossible for relays Q to become energized in the reverse 10 direction for permitting an eastbound train to enter the portion $B-H$ of the stretch of track shown in the drawings.

I will next assume that the operator desires to clear signals S^{1a} and S^{3a} for an eastbound train. He will, therefore, move lever V^1 to its r position. This causes contact 4^{nr} of lever V^1 to break the stick circuit for relay P^B which thereupon becomes deenergized, causing relay K^B to also become deenergized. With relay K^B deenergized, a circuit is completed for energizing relays Q in the reverse direction, passing from terminal x , through the front point of contact 31 of relay K^B , winding of relay Q^3 , contact 30 of relay T^6 , contact 29 of relay T^5 , contact 28 of relay U , contact 27^a of relay T^4 , winding of relay Q^2 , contact 26 of relay T^3 , winding of relay Q^1 , back points of contacts 25^{KB} and 36^{KB} , wires 35 and 33 , and from point of contact 32 of relay K^B to terminal o . Relay Q^1 , being thus energized in the reverse direction, closes its polar contact 38 and 25 closes its contact 39 at its front point, causing relay R^a to become energized by a circuit passing from terminal x , through contact 37^{KB} , polar contact 38 , front point of contact 39 of relay Q^1 , and the winding of relay R^a to terminal o . Relay R^a , upon becoming thus energized, completes, at its contact 40 , the circuit for signal S^{3a} , causing the arm of signal S^{3a} to move to the proceed position. With lever V^1 in its r position, the 30 energization of relay R^a completes a circuit for causing signal S^{1a} to indicate "proceed", passing from terminal x , through contact 18 of relay R^a , contact 20 of switch J^1 , contact 21 of lever V^1 , contact 22^{T^2} , and the mechanism of signal S^{1a} to 35 terminal o .

From the time an eastbound train passes signals S^1 until it leaves section $B-C$, relay K^B will remain deenergized, and while it is passing from signal S^{3a} to signals S^8 , the track relays T^3 , T^4 , T^5 and T^6 will become successively deenergized, causing the circuit for relays Q to be constantly deenergized. This makes it impossible for relays Q to become energized in the normal 40 direction for permitting a westbound train movement while an eastbound train is moving from B to G .

After the first eastbound train passes signals S^3 , a second eastbound train will be given a "call-on" indication by the arm of signal S^{3b} . This is 60 accomplished through the deenergization of relay Q^1 by the deenergization of relay T^3 . With relay Q^1 deenergized, relay R^b will be energized by a circuit passing from terminal x , through contact 37^{KB} , polar contact 38 , back point of contact 39 of relay Q^1 , and the winding of relay R^b to terminal o . The circuit for causing signal S^{3b} to indicate proceed will therefore be closed at back contact 65 of relay R^a and front contact 41 of relay R^b .

If a westbound train is to use switch J^2 in its reverse position, the operator will clear signal S^{9a} as previously traced, and will then move lever V^2 to its r position. When the train arrives at switch J^2 , one of the trainmen will open the door 75

of the case which contains lock magnet *d* and lever *X*, thereby causing door contact *f* to close. The entrance of a train into section D—E causes relay *T*⁴ to become deenergized, thereby completing a pick-up circuit for relay *t* passing from terminal *x*, through contact **50** of relay *T*⁴, and the winding of relay *t* to terminal *o*. The operation of lever *V*² to its *r* position by the operator has already caused relay *Y* to become energized 10 in the reverse direction by a circuit passing from terminal *x*, through contact **51** of lever *V*² in its reverse position, winding of relay *Y*, back contact **52** of relay *N*, and contact **53** of lever *V*² in its reverse position to terminal *o*. When the trainman causes door contact *f* to close, relays *W* and *N* will therefore become energized in series by a circuit passing from terminal *x*, through contact **54** of relay *Y*, winding of relay *N*, contact **55** of relay *t*, contact **56** of relay *Q*² in its normal position, door contact *f*, winding of relay *W*, wire **35**, and the front point of contact **36KB** to terminal *o*.

Relay *N*, upon thus becoming energized, opens, at the back point of its contact **64**, the lighting circuit for lamp *e*^N, and closes, at the front point of contact **64**, the lighting circuit for lamp *e*^R, to indicate to the operator that the switch locking has been released so that the distant track switch can be reversed by the trainman.

With relay *W* thus energized, lock magnet *d* becomes energized by a circuit passing from terminal *x*, through contact **59** of relay *W*, and the winding of magnet *d* to terminal *o*. Magnet *d*, upon becoming energized, lifts its armature with dog **69** out of engagement with notch **61** of segment *g*, thereby permitting movement of lever *X*, and at the same time operates a visual indicator comprising a miniature semaphore, as shown in the drawings to inform the trainman that the locking of lever *X* is released. The trainman will therefore move lever *X* to its *r* position, thereby withdrawing dog *a* from bar *b*. The trainman will then proceed to reverse switch *J*². The movement of lever *X* to its *r* position has already opened the circuit for relay *U*, causing this relay to become deenergized. The deenergization of relay *U* causes a branch path to be completed for the control circuit for relay *W*, passing from the winding of relay *N*, through contact **58U** to the winding of relay *W*. If the trainman should now close the door of the case for lever *X* permitting door contact *f* to again open while lever *X* is in its *r* position, relay *W* will continue energized by its circuit through contact **58U**. Hence, if another switch besides switch *J*² is also controlled by relay *W*, the lock magnet corresponding to magnet *d*, for the other switch would continue energized, thus permitting the trainman to operate the other switch if he should so desire as long as contact **58U** is closed.

If an eastbound train is to set out a car over switch *J*² reversed, the operator will move lever *V*¹ to its *r* position as already described, and will then move lever *V*² to its *r* position. The circuit for relays *Q* being now energized in the reverse direction, contact **56** of relay *Q*² is closed in its reverse position. When the train arrives on the detector section D—E, and when the trainman has caused contact *f* to close, relay *W* will remain released, as indicated by the condition of the visual indicator controlled by magnet *d*, and the trainman is thus informed that it will still be necessary for him to operate the normally open push button contact *h* before relay *W* will become energized. Since section D—E is occu-

pied, track relay *T*⁴ is released, and operation of contact *h* completes a second branch path for the circuit for relays *W* and *N*, passing from the winding of relay *N*, through contact *h*, back contact **51T**⁴, and contact **56** of relay *Q*² in its reverse position to contact *f*. Magnet *d* being now energized, the trainman can operate lever *X* and switch *J*², as already described.

If an engine is to move eastward to switch *J*² and obtain a car and then return westward, the operator will first provide for the eastbound movement by operating lever *V*¹ to its *r* position and, after the engine has passed signal *S*^{3a}, he will return lever *V*¹ to its *n* position, thereby conditioning a circuit for energizing relays *Q*¹ and *Q*² in the normal direction when the train moves out of section C—D, passing from terminal *x*, through contact **23** of relay *R*^b, contact **24** of relay *R*^a, front point of contact **25KB**, winding of relay *Q*¹, contact **26** of relay *T*³, winding of relay *Q*², contact **27b** of relay *T*⁴, a resistance unit **34**, wire **35**, and the front point of contact **36KB** to terminal *o*. It will now be unnecessary for the trainman to operate push button *h* as previously described, since the circuit for relays *W* and *N* will now be closed through contact **56** of relay *Q*² in its normal position.

From the foregoing description and the accompanying drawings, it follows that apparatus embodying my invention comprises a scheme of traffic locking in which the directional control for signals is effected by approach locking relays for the two directions of traffic. The signals for a given direction of traffic are controlled by a back contact of the approach locking relay for that direction and by a front contact of the approach locking relay for the opposite direction. Hence the entering signal, such, for example, as signal *S*^{1a}, for a given direction can be cleared only when the approach locking relay *P*^H for the opposite direction is energized, thus insuring that signals *S*⁹ for the opposite direction are indicating "stop". Furthermore, with this arrangement, the signals for a given direction of traffic movement can be cleared only when the approach locking relay for that direction is deenergized, thereby insuring that the signals for the opposite direction can not become cleared while the signals for the first direction are indicating "proceed".

Apparatus embodying my invention also comprises a scheme of circuits for an outlying lock, by means of which the control, and normal and reverse indication for all switches controlled by the lock circuit require the use of only one wire in connection with the traffic locking control wires. With this arrangement, the approach locking relay for signals controlling traffic entering a given stretch against the current of traffic serves as an approach locking relay for the outlying switch lock as well.

Although I have herein shown and described only one form of railway traffic controlling apparatus embodying my invention, it is understood that various changes and modifications may be made therein within the scope of the appended claims without departing from the spirit and scope of my invention.

Having thus described my invention, what I claim is:

1. In combination, a section of railway track including a switch, a second section of said track adjacent said first section, a signal for governing traffic movements over said switch, a track circuit for said first section including a track re-

lay, a track circuit for said second section including a second track relay, a stick relay, a pick-up circuit for said stick relay including a back contact of said first track relay in series with a front contact of said second track relay, a stick circuit for said stick relay energizable when and only when said signal is controlled to indicate "stop", a second stick relay, a pick-up circuit and a stick circuit for said second stick relay one of which is controlled by said first track relay and the other of which is controlled by said first stick relay, and means controlled by said second stick relay for controlling said switch.

2. In combination, a track circuit including a track relay, a second track circuit including a second track relay, a signal, a second signal, signal control means for controlling said first signal, a stick relay, a pick-up circuit and a stick circuit for said stick relay one of which includes a back contact of said first track relay in series with a front contact of said second track relay and the other of which is controlled by said signal control means, a second stick relay, a pick-up circuit and a stick circuit for said second stick relay one of which is controlled by said first track relay and the other of which is controlled by said first stick relay, and means controlled by said second stick relay for controlling said second signal.

3. In combination, a track circuit including a track relay, a second track circuit including a second track relay, a signal, a control device, a stick relay, a pick-up circuit and a stick circuit for said stick relay one of which includes a back contact of said first track relay in series with a front contact of said second track relay and the other of which is controlled by said control device, a second stick relay, a pick-up circuit and a stick circuit for said second stick relay one of which is controlled by said first track relay and the other of which is controlled by said first stick relay, and means controlled by said second stick relay for controlling said signal.

4. In combination, a track circuit including a track relay, a second track circuit including a second track relay, a signal, a control device, a stick relay, a pick-up circuit and a stick circuit for said stick relay one of which is controlled by a back contact of said first track relay in series with a front contact of said second track relay and the other of which is controlled by said control device, a second stick relay, a pick-up circuit and a stick circuit for said second stick relay one of which is controlled by said first track relay and the other of which is controlled by said first stick relay, and means controlled by said control device and by said second stick relay for controlling said signal.

5. In combination, a track circuit including a track relay, a second track circuit including a second track relay, a signal, a second signal, a control device, a stick relay, a pick-up circuit and a stick circuit for said stick relay one of which is controlled by a back contact of said first track relay in series with a front contact of said second track relay and the other of which is controlled by said control device, a second stick relay, a pick-up circuit and a stick circuit for said second stick relay one of which is controlled by said first track relay and the other of which is controlled by said first stick relay, means controlled by a back contact of said second stick relay for controlling said first signal, and means controlled by a front contact of said second stick relay for controlling said second signal.

6. In combination, a stretch of railway track, a first plurality of traffic governing devices spaced along said stretch for governing traffic movements in a first direction, a second plurality of traffic governing devices spaced along said stretch for governing traffic movements in a second direction, an approach track circuit including a track relay adjacent one end of said stretch, a control device, a stick relay, a pick-up circuit and a stick circuit for said stick relay one of which is controlled by said approach track relay and the other of which is controlled by said control device, a second approach track circuit including a second track relay adjacent the opposite end of said stretch, a second control device, a second stick relay, a pick-up circuit and a stick circuit for said second stick relay one of which is controlled by said second approach track relay and the other of which is controlled by said second control device, means controlled by a front contact of said first stick relay and by a back contact of said second stick relay for controlling said first plurality of governing devices, and means controlled by a front contact of said second stick relay and by a back contact of said first stick relay for controlling said second plurality of governing devices.

7. In combination, a stretch of railway track, a signal adjacent one end of said stretch for governing traffic movements into said stretch in a given direction, a second signal adjacent the opposite end of said stretch for governing traffic movements into said stretch in the opposite direction, an approach track circuit including a track relay for said first signal, a control device for controlling said first signal, a stick relay, a pick-up circuit and a stick circuit for said stick relay one of which is controlled by said approach track relay and the other of which is controlled by said control device, a second approach track circuit including a second track relay for said second signal, a second control device for controlling said second signal, a second stick relay, a pick-up circuit and a stick circuit for said second stick relay one of which is controlled by said second approach track relay and the other of which is controlled by said second control device, means controlled by a back contact of said first stick relay and a front contact of said second stick relay for controlling said first signal, and means controlled by a back contact of said second stick relay and a front contact of said first stick relay for controlling said second signal.

8. In combination, a railway traffic governing device having a normal and a reverse position, a manually controllable contact, an indication device, a control circuit for controlling said governing device including said indication device and said manually controllable contact in series, an indication contact which becomes closed when said governing device is moved out of its normal position, and a branch path for said circuit including said indication contact in multiple with said manually controllable contact.

9. In combination, a railway track switch manually operable to a normal or to a reverse position, a normally restrained manually operable member for locking the switch in its normal position, a magnet for releasing said member effective when energized to permit the switch to be reversed, a remotely controlled circuit for controlling said magnet, an indication relay arranged to be energized only when the switch is locked in its normal position, a signal for governing traffic over said switch and arranged to

display a clear indication only when the indication relay is energized, a normally open manually operable contact adjacent said switch in the circuit for controlling said magnet, and a shunt 5 for said contact comprising a back contact of said indication relay.

10. In combination, a railway track switch manually operable to a normal or to a reverse position, a normally restrained manually operable 10 member for locking the switch in its normal position, a magnet for releasing said member, a control contact for said magnet located at a remote point and having a normal and a reverse position, a circuit for the control of said magnet 15 including a line wire and the control contact in its reverse position, indication means associated with said contact for visually indicating when said circuit is closed, means effective when the circuit is closed for preventing said control contact being moved from its reverse to its normal position and means for opening the circuit to release the indication means effective only when the track switch is locked in normal position.

11. In combination, a stretch of railway track, 25 a signal adjacent one end of said stretch for governing traffic movements into said stretch in a given direction, a second signal adjacent the opposite end of said stretch for governing traffic movements into said stretch in the opposite direction, a circuit serially connecting two route relays respectively associated with said signals and which circuit is energizable at both ends, two circuit controllers one associated with each end of said circuit each operable to effect energization 30 of said circuit but both normally ineffective, independent manually controlled devices located at a central office for respectively operating said circuit controllers for energizing said circuit from one end or the other, means for assuring that 35 only one of said controllers can be effective at a time, an operating circuit controlled by each route relay when energized for clearing the associated signal, and means for causing only the operating circuit controlled by the route relay 40 at the end at which the circuit controller is operated to be effective.

12. In combination, a stretch of railway track including a track switch, a signal adjacent one end of said stretch for governing traffic movements into said stretch in a given direction, a second signal adjacent the opposite end of said stretch for governing traffic movements into said stretch in the opposite direction, a circuit serially connecting two route relays respectively associated with said signals, and which circuit is energizable at both ends, two circuit controllers one associated with each end of said circuit each operable to effect energization of said circuit but both normally ineffective, independent manually 50 controlled devices located at a central office for respectively operating said circuit controllers to energize the circuit at one end or the other, means for assuring that only one of said controllers can be effective at a time, other means for assuring 55 that said circuit can be energized only when said switch is in a given position, and an operating circuit for each signal rendered effective to clear its signal only when the associated route relay is picked up and the associated circuit controller 60 is in its operated position.

13. In combination, a stretch of railway track provided with a circuit serially connecting two route relays respectively associated with opposite directions of traffic and which circuit is responsive to the condition of the traffic rails of 75

the stretch, a current source associated with each direction of traffic for supplying current to said circuit but both normally ineffective, a signal normally indicating "stop" located at each end of the stretch to govern traffic in opposite directions through the stretch, a control circuit for each signal having two normally open contacts, means controlled by the energization of the route relay associated with the direction of traffic which is governed by a signal for closing one of said open 10 contacts of the control circuit of that signal, a first means controlled from a central office for closing the second open contact of the control circuit of that signal, a second means controlled from the central office to render the current 15 source associated with the direction of traffic governed by that signal effective to supply current to the route circuit, and means to prevent the central office means from rendering more than one current source effective at a time. 20

14. In an interlocking system for railroads, a stretch of track divided into a plurality of track sections, two signals one at each end of said stretch of track for governing traffic in opposite directions thereover, track switches associated 25 with said track sections, means for operating said track switches, control levers for each of said signals, a directional stick relay for each track section containing a track switch, one of said stick relays being for one direction and the other 30 of said stick relays being for the opposite direction, means locking at least one of said track switches when the directional stick relay for the corresponding track section is deenergized, and means clearing one of said signals only when the 35 corresponding control lever is operated and the directional stick relay for the corresponding direction is deenergized.

15. In combination, a railway track switch, a lock relay which when deenergized prevents operation of the track switch, a manually operable switch control lever located at a point remote from the switch, a manually operable contact located adjacent the switch for rendering said lever effective to control the switch, a control 40 circuit including said lock relay and having two branches each of which includes a contact closed when said lever is operated to control the switch one of said branches also including said manually operable contact, a track relay controlled by 45 traffic conditions adjacent the switch, and means controlled by said track relay for completing said control circuit under favorable track conditions when said lever is operated, even though said manually operable contact is not operated. 50

16. In combination, a railway track switch, a control lever at a point remote from the switch, a relay controlled by said lever and by traffic conditions adjacent the switch, means effective if the relay is released to prevent operation of the 60 switch, a manually operable contact adjacent the switch for at times picking up said relay, and an indicator adjacent said contact for visually indicating when said relay is released and said contact is to be operated.

17. In combination, a railway track switch, a control lever at a point remote from the switch, a relay controlled by traffic conditions adjacent the switch, a circuit for said relay governed by 70 said control lever, means effective if the relay is released to prevent operation of the switch, a manually operable contact adjacent the switch for at times closing said circuit, indication means adjacent said contact controlled by said relay for indicating when said contact is to be operated, 75

and indication means adjacent said control lever responsive to the flow of current in said circuit for indicating when said contact has been operated.

5 18. In combination, a railway track switch, a lock relay which when deenergized prevents operation of the track switch, a circuit for said relay including in series a normally open manually operable contact adjacent the switch and a 10 manually controlled contact at a point remote from the switch, and means normally effective under traffic conditions favorable for the operation of the switch for bridging said normally open manually operable contact.

19. In combination, a detector section of railway track including a track switch, a lock relay which when deenergized prevents operation of the track switch, a first normally open manually controlled contact at a point remote from the 5 switch, a second normally open manually controlled contact adjacent the switch, a circuit for said lock relay including said two contacts in series, and means for completing said circuit to pick up said lock relay effective if said contacts are simultaneously closed when said detector section is occupied. 10
